PICKUP HEAD FOR A PHONOGRAPH

Walter O. Stanton, Laurel Hollow Road,
Laurel Hollow, N.Y.

Filed Feb. 6, 1964, Ser. No. 78,548

Term of patent 14 years

(Cl. D26—14)

FIG. 1

FIG. 4

FIG. 2

FIG. 5

FIG. 3

FIG. 1 is a top plan view of a pickup head for a phonograph embodying my design.

FIG. 2 is a side elevational view of the phonograph pickup.

FIG. 3 is a bottom plan view of the phonograph pickup.

FIG. 4 is a back end view of the phonograph pickup.

FIG. 5 is a front end view of the phonograph pickup.

I claim:

The ornamental design for a pickup head for a phonograph, as shown and described.
